C. T. WARD

TALKING MACHINE

Filed May 1, 1923

FIG. 1

UNITED STATES PATENT OFFICE.

CHARLES T. WARD, OF CUPAR, SASKATCHEWAN, CANADA.

TALKING MACHINE.

Application filed May 1, 1923. Serial No. 635,937.

To all whom it may concern:

Be it known that I, CHARLES T. WARD, of the town of Cupar, in the Province of Saskatchewan, Canada, have invented certain new and useful Improvements in Talking Machines, of which the following is the specification.

The invention relates to improvements in talking machines and an object of the invention is to provide means whereby a used needle can be quickly replaced by a new needle and without requiring the releasing of an adjustable part, such as a jam screw, as is customarily employed.

15 A further object is to construct a device attachable to the tone arm and the sound box, the device providing a compartment for the storing of new needles and being arranged such that the attendant by rotating 20 the sound box can effect the discharge of the used needle and the insertion of a new needle selectively picked from the storage compartment.

25 A further object is to construct the appliance in a simple, cheap and durable manner and such that it can be readily attached to existing types of talking machines.

With the above more important objects in view the invention consists essentially 30 in the arrangement and construction of parts hereinafter more particularly described and later pointed out in the appended claims, reference being had to the accompanying drawing in which:

35 Fig. 1 is a vertical sectional view through the upper part of a talking machine and showing the tone arm and sound box in side elevation and with my invention mounted thereon.

40 Fig. 2 is an enlarged detailed horizontal sectional view at 2—2' Fig. 1, certain parts being shown in plan view.

Fig. 3 is an enlarged detailed vertical sectional view at 3—3' Fig. 2.

45 Fig. 4 is a vertical sectional view at 4—4' Fig. 2.

Fig. 5 is an enlarged detailed vertical sectional view at 5—5' Fig. 2.

Fig. 6 is a horizontal sectional view at 50 6—6' Fig. 3.

Fig. 7 is a horizontal sectional view at 7—7' Fig. 3.

55 In the drawing like characters of reference indicate corresponding parts in the several figures.

The casing 1 of the talking machine is

closed at the upper end by the customary hinged top 2 and is interiorly fitted with a motor board 3 which supports the motor 4, the driven spindle 5 of which carries the 60 turn table 6, on which the customary record is placed. The tone arm 7 is of the usual form, being swivelly carried by the rear part of the motor board and communicating through the motor board with the 65 horn or amplifying chamber 8. The forward end of the tone arm is provided with the usual pivoted neck 9 which is adapted to swing in the vertical plane, and the neck carries a sound box 10, the same being 70 rotatably mounted on the end of the neck. The sound box is provided on the customary diaphragm 12 and from this the needle of the arm 13 extends, the extending end of the arm being attached in the usual 75 manner to the sound box.

The pivotal mountings of the neck and the sound box are not new; the neck being so mounted that the needle carried by the sound box can be swung to playing position 80 or to non-playing position, and the pivotal mounting of the sound box being either to permit of the removal of the sound box or the bringing of the needle to playing position.

85 The non-playing position of the neck is shown in Figure 1.

I provide, however, a means for locking the sound box against rotation in the playing position thereof, such embodying a ball 90 14 which is carried by the sound box and rides the outer face of the neck, and is held in place by a spring 15 attached to the sound box. A runway 16 is provided in the neck for the ball, and the runway at one end terminates in a pocket 17 into which the ball can escape and when so entered is adapted to releasably lock the sound box in playing 95 position to the neck. This is necessary, as otherwise it would be possible for the end of the neck to drop down and let the sound box drag on the record.

The free end of the arm 13 terminates in a more or less semi-circular groove 18, which is adapted to receive one side of the needle 105 19, the other side of which is engaged by a spring catch 20 attached to the needle arm, the spring member releasably holding the needle in place.

By observing Fig. 3 it will be seen that 110 there is a V-shaped entry space 21 and a V-shaped outlet or expelling space 22 above

and below the caught needle, this construction permitting of the entrance of the needle from below and the expelling of the same upwardly.

5 To the tone arm I attach a bracket 23, the free end of which supports a needle storage box 24, the storage box having a hopper shaped bottom 25 fitted with a transverse slot 26 which receives a vertically disposed needle selector 27, the selector having the ends slidably mounted in the ends of the box. The upper edge thereof is provided with a lengthwise extending groove 28 and the sides are vertically slotted as indicated at 29 and 30. The ends of the latter slots limit the up and down movement of the selector. The selector is positioned such that it will take a position directly beneath the needle carried by the needle arm when the sound box is rotated, as later described. This latter position is shown in Figure 3.

25 A lever 31 is pivotally attached to a bracket 32 carried by the tone arm and one end of the lever is formed into a finger 33 underlying the neck, whilst the other end thereof is pivotally attached by a pivot bolt 34 to the lower end of the needle selector. A brace bar 35 reinforces the brackets 23 and 32.

30 When this device is to be used one places a number of needles in the storage box or compartment with the points thereof all facing in one direction.

35 Assuming that one has just finished playing a record and desires to change the needle; at this time the used needle is on the record and the neck is in playing position. Consequently, the finger 33 is free of the neck and the selector 27 is in its lower position, having dropped down under the action of its own weight and the weight of the long end of the arm 31. In this position of the selector the groove 28 is at the bottom of the box 24 and by virtue of the hopper shaped bottom of the box the needles naturally roll in to occupy the position previously held by the selector. When one swings the neck up and back to bring the sound box to non-playing position, he brings the neck into contact with the finger 33 and in so doing causes the arm 31 to raise the selector to its upper position and the selector, in raising, picks up a needle, the needle being carried in the groove 28 and being elevated clear of all the other needles. The attendant then rotates the sound box to turn the needle arm from the position shown in dotted outline in Fig. 1 to that shown in full outline, such movement bringing the needle, which has just been playing, to a position directly above the new needle carried in the groove 28. Consequently, a down movement of the old needle, brought about by rotating the sound box, will cause

the new needle to force the old needle out through the clearance space 22 and the new needle to take the position occupied by the discharged old needle. Having accomplished this, one then rotates the sound box back to 70 bring the needle arm and needle to the position shown in dotted outline in Fig. 1, in which position the ball is in the slot 17. Then, by rotating the neck in the usual manner he can bring the new needle into playing 75 position in contact with the record.

Obviously, the attendant has nothing to release, but simply has to manipulate the sound box and neck, in the manner disclosed, to insert the new needle. It is, of course, to 80 be understood that the spring 20 is sufficiently strong to hold the inserted needle tightly in place for playing purposes.

What I claim as my invention is:

1. The combination with a rotatably mounted sound box, and the needle carrying arm carried thereby and rotatable therewith, of a needle storage box, mechanically operated means for selectively picking a needle from the storage box and elevating the same to an exposed position in the path of the rotated needle arm, and a spring catch associated with the needle, said spring catch being adapted to receive and hold the needle selected from the storage box in the 95 rotation of the sound box.

2. The combination with a rotatably mounted sound box and the needle arm carried thereby and rotatable therewith, of a spring catch associated with the needle arm 100 and adapted to receive and hold a needle, a suitably mounted needle storage box and means for selectively picking a needle from the storage box and bringing the same into the path of travel of the rotated needle arm, 105 whereby the selected needle will be caught by the catch in the rotation of the sound box.

3. The combination with a tone arm, a neck pivotally carried by the tone arm, a 110 sound box rotatably mounted on the neck and the needle arm carried by and rotatable with the sound box, of a needle storage box carried by the tone arm, a needle selector slidably mounted in the box and adapted 115 when raised to pick up a needle and bring the same to an exposed position in the path of the rotated needle arm, a pivoted lever carried by the tone arm pivotally connected to the selector and engageable with the neck 120 and adapted, in the swinging movement of the neck, to operate the selector, and a spring catch carried by the needle arm and adapted to catch and hold the exposed needle in the rotation of the sound box. 125

4. The combination with a tone arm, a rotatably mounted neck carried by the tone arm, a sound box rotatably mounted on the neck and a needle arm carried by the sound box and rotatable therewith, of a spring 130

catch carried by the needle arm and adapted to receive and hold a needle, a needle storage box carried by the tone arm, said storage box having a hopper shaped bottom, a selector slidably mounted for vertical movement in the needle box and adapted when moved upwardly to select a needle and bring the selected needle to an elevated position in the path of the rotated needle arm and cause the selected needle to be caught by the catch, a lever pivotally carried by

the tone arm and having one end pivotally connected to the selector and the other end underlying the neck, said lever being adapted to actuate the selector by contact with the rotating neck.

Signed at Cupar this 20th day of January, 1922.

CHARLES T. WARD.

In the presence of—

J. D. MACHON,
M. G. ROOKE.
